UNITED STATES PATENT OFFICE

2,111,338

MECHANISM FOR SUPPLYING SHEET MATERIAL

Elmer Lovell Smith, Longmeadow, and Carlton Wetsel, Springfield, Mass., assignors to Package Machinery Company, Springfield, Mass., a corporation of Massachusetts

Original application October 1, 1935, Serial No. 43,088. Divided and this application June 22, 1936, Serial No. 86,530

8 Claims. (Cl. 271—46)

This invention relates to mechanisms for supplying sheet material to wrapping machines or the like. More particularly, it relates to mechanisms of this character which deliver sheets successively, either as they are severed from a web or are supplied from a stack of pre-cut sheets, to a predetermined position in the machine being served, as for example the folding mechanism of a wrapping machine.

10 One object of the invention is to provide a device of this character in which the delivery of the sheet at the proper point may be controlled by a simple adjustment without substitution or rearrangement of the cutting or feeding means. A 15 further object is to secure a simplification of structure and operating advantages as will be apparent from the following specification and claims.

This application is a division of our copending 20 application Serial No. 43,088, filed October 1, 1935.

In the accompanying drawings which illustrate one embodiment of the invention,

Fig. 1 is a side view, partly in section showing 25 the invention as applied to the wrapping machine of our above mentioned copending application;

Fig. 2 is a detail view of the tension equalizing mechanism for the initial feeding of the web;

Fig. 3 is a detail of the adjustable cam mechanism for regulating the termination of the wrapper feeding operation;

Fig. 4 is a detail of the paper feed;

Fig. 5 is a detail of one of the paper supporting and feeding rolls;

35 Fig. 6 is a detail in side elevation of the paper feeding roll shown in Fig. 5;

Fig. 7 is a detail showing the manner in which the movable paper feeding rolls are actuated;

Fig. 8 is a side elevation showing the parts of 40 the paper feeding mechanism in the positions they occupy during the feeding of the paper;

Fig. 9 is a similar view showing the same parts in the positions they occupy after the termination of the wrapper feeding operation; and

45 Fig. 10 is a detail sectional view substantially on line 10—10 of Fig. 1.

The paper feeding mechanism is supported on a base frame 20 which also serves to support the wrapping mechanism. The articles to be wrapped are fed beneath a plate 25 having a vertical extension 26 which serves as one side of an elevator well or article guiding chute across the top of which the wrapper is fed. The articles are carried upwardly to the entrance of the wrapping channel by an elevator 28 mounted on a bar 31

reciprocable in guides 32 and is operated by a link 33 pivoted to a bell crank lever 34 which derives its motion by means of a link 35 from a crank 36 on a constantly rotating shaft 37. The elevator carries the article *a* with the wrapper 5 upwardly between spring plate 40 and a fixed plate 41, to fold the wrapper about three sides of the article, to a position above plate 41 as indicated in Fig. 1 where its lower forward edge is engaged by a flapper 46 working in a slot in 10 plate 41 against the force of a torsion spring 47. This mechanism is fully described in our above identified application and need not be further described here.

The wrapping material is initially supplied to 15 the machine on a spool 105 (Figs. 1 and 2) from which it passes over a tension roll 106 provided with the usual equalizing rack and pinion connection 107 and drawn in a direction to take up the slack in the web by a spring 108. The web 20 next comes into engagement with alternating wires 109 and 110 which corrugate the material slightly in order to increase its rigidity when pushed through the cutting mechanism, these wires lying between cork rolls 111 geared to and 25 resting on a steel roll 112 (Figs. 1 and 4). A change gear 113 connects a gear on the shaft of the roll 112 with a gear 114 on a shaft 115 conveniently driven as by a chain and sprocket connection from the shaft 37 previously referred 30 to. The rolls 111 and 112 are preferably continuously driven and project the corrugated web across a support 116 and over a block 117 bearing a stationary knife blade 118. Cooperating with this stationary knife is a rotatable knife 35 119 carried by a rotating shaft 120 driven from the gear 114 by a gear 121. This shaft preferably carries disk like paper guiding fins 122 which serve to keep the leading end of the freshly severed web from following the rotating knife. 40 This much of the web handling mechanism is largely conventional and need not be considered in more detail.

The mechanism for feeding the severed sheets forwardly into the wrapping means is in some 45 respects similar to that shown in the Fischer and Fuller Patent 1,927,585, Sept. 19, 1933, but is simpler in construction and has certain operational advantages. Extending from the cutting rolls to and past the folding box are a pair of laterally spaced belts 125 adapted to contact 50 with the upper side of the severed wrapper. Each of these belts passes around a set of pulleys 126, 127, 128 and 129, one set being shown in Fig. 8. Although the pulleys themselves do not 55

appear in Fig. 10, it will be apparent from the position of the belts 125 in that figure that one set of pulleys is associated with and mounted on the stationary cross bar 88 and the other set is associated with and mounted on the adjustable cross bar 42 which is held in adjusted position by a bolt and slot connection 130 with the frame. Each of these bars has a plate 131 which extends between the adjacent runs of the respective belt and both prevents friction and gives a support. The shaft of the pulleys 126 is driven by a gear 132 from the gear 121, that pulley 126 located on the movable cross bar having a splined connection with the shaft so that it will be driven positively in any position of adjustment.

The belts travel continuously, and the paper feed is secured by pressing the leading end of the web or the severed sheet upwardly against the belt as in the Fischer and Fuller patent. The mechanism for accomplishing this is, however, radically different, and is divided into two parts, one being permanently engaged with the wrapping material and the other being vertically movable so that the feeding action can be terminated at the proper point. As in the Fischer and Fuller patent the linear speed of the belts is preferably greater than the speed with which the leading end of the web is being projected by the rolls 111, 112, and the belts slip over the projecting web end, giving a stroking action to it and keeping it taut during the cutting action. As soon as the sheet is severed from the web it partakes of the higher speed of the belts, running away from the leading end of the web from which it was cut and producing the desired spacing between successively delivered sheets.

The part of the wrapper engaging mechanism permanently in pressing engagement with the belts consists in a pair of separated roll bearing frames 135 (Fig. 8) supported at their ends on brackets 136 and 137 mounted on rods 138 and 139. One of each similar pair of brackets is fixed in lateral position so as to remain in fixed relation to the cross bar 88, while the other is adjustable on its supporting rod to permit it to be shifted for different widths of paper. As is best shown in Figs. 5 and 6 the rolls 140 are separately mounted on arms 141 pivoted on pins 142 secured in the frame. Each arm has a projection 143 engaging a tie member 144 to limit the angular motion of the arm, and is pressed in a direction to carry the roll against the belt by a spring 145. If it is desired to provide the wrapper with a stripe of sealing liquid along a longitudinal margin during its passage into the machine, this can be done by a wheel 165 (Fig. 1) dipping into a trough 166 and laterally adjustable in a bar 167. The wheel is positively driven by a chain connection 168 from the shaft of gear 132.

As will be clear from Figs. 8 and 9 the rolls extend only part way along the frames, the remainder of the frames being formed with buttress-like teeth 146 which prevent smearing of the longitudinal strip of glue when the paper is drawn into the folding box, and which by reason of their shape offer slight resistance to the forward motion of the sheet. The belts being on top only are not liable to contact with the glue.

The frames 150 which form the intermittent part of the wrapper engaging mechanism are mounted in the space within the spaced members of the frames 135 as is best shown in Fig. 7. These second frames are carried at one end by levers 151 (Fig. 8) rotatably fixed to the rods 138

and at the other end by levers 152 rotatably fixed to the rods 138. By rocking the rod 138 the frames 150 will be caused to move up and down with a parallel movement; the frames 135 which are rigid with their brackets 136 and 137, being unaffected by this motion since these brackets are free on their supporting rods. The frames 150 carry rollers 153 mounted similarly to the rolls 140 except that they are located further along the frames, coming adjacent that part of the frames 135 which is fitted with the teeth 146. To elevate and depress the frames 150 periodically the rod 138 is provided with an arm 155 (Fig. 3) attached at one end by a spring 156 to the frame and bearing at the other a cam roll 157. This cam roll bears against a cam 158 secured to the shaft 115 by an adjustable clamp 159. The cam and the shaft can be readily provided with a scale and a pointer respectively, so that the position of angular adjustment can easily be determined. Rotation of the cam relative to the shaft serves to vary the time at which the frame 150 is lowered and hence determines the time at which the feeding motion of the severed wrapper towards wrapping position is terminated. The time at which the frame is raised will, of course, also be varied by rotating the cam, but this is unimportant as the elevation of the frame occurs at a time when the sheet is still being advanced by the fixed rollers 140.

The operation is as follows. As the leading end of the web is projected past the cutting mechanism by the pushing action of the rolls 111 and 112 it will enter between the belts 125 and the first of the series of fixed rolls 140. Since the belts are traveling faster than the rolls 111, 112, slippage will occur, drawing the web taut for the cutting operation. As soon as the cutters have acted, the severed sheet which now is well within the grasp of the belt and the fixed rolls, will start to advance at the speed with which the belt is moving. At somewhat the same period the vertically movable rolls rise, furnishing a continuous guide for pressing the wrapper against the belts throughout the lengths of the frames. Forward motion of the wrapper at the speed of the belts continues until the frame 150 is lowered by the action of cam 158. The wrapper descends with the rolls 153, which are driven only by contact with the belt, and rests upon these rolls and upon the teeth 146 of the frames 135. At the same time the forward end of the wrapper contacts with a paper stop 160 (Fig. 1) which is adjustably mounted so as to be adaptable for different lengths of wrapper. The wrapper rests in this position until it is contacted by the article *a* being raised by the elevator 29 through the well formed by the plates 26 and 28 and the end guides 161 (Fig. 9). Additional guides for the wrapper, similar to the toothed end of the frames 135, can be located on either side of the elevator well if desirable in order to maintain extra large wrappers in flat condition.

We claim:

1. Mechanism for delivering sheets to wrapping machines and the like, comprising one or more continuously running belts, a series of rolls positioned below the belts, and means for moving the rolls upwardly to press a sheet against the belt or downwardly to free the sheet from the belt.

2. Mechanism for delivering sheets to wrapping machines and the like, comprising one or more continuously running belts, a series of rolls po- 75

5 sitioned below each belt, and means for moving the rolls upwardly to press a sheet against each belt and thus to cause its forward motion, or downwardly to free the sheet from engagement with the belt, and supports arranged alongside the rolls in position to receive the sheet when the rolls are lowered.

10 3. Mechanism for delivering sheets to wrapping machines and the like, comprising one or more continuously running belts, a series of fixed freely rotatable rolls positioned underneath each belt for a portion of its length, a second series of freely rotatable rolls positioned underneath each belt for a further portion of its length, and 15 means for moving said second series of rolls upwardly against the belt to form a continuation of the sheet feeding channel formed by the belt and the first series of rolls, or downwardly to free the sheet from contact with the belt and terminate its forward motion.

20 4. Mechanism for delivering sheets to wrapping machines and the like, comprising one or more continuously running belts, a series of freely rotatable rolls positioned below each belt and 25 during the sheet feeding period of the device in contact therewith, a stop projecting into the path of the sheets, and means for lowering the rolls out of feeding contact with each belt as the leading edge of the sheet is about to contact 30 with the stop.

5. A device for controlling the leading end portion of a web as it is being severed to form a sheet and for advancing the so severed sheet from a severing means, which comprises a plurality of parallel continuously moving belts spaced laterally apart and located at one side 35 of the path of travel of the leading end of the web, a plurality of freely rotatable rolls spaced apart longitudinally along each belt and located 40 at the other side of the path of travel of the web, and means for moving at least some of the rolls away from the belt to terminate the driving friction of the belt on the sheet severed from the leading end of the web.

45 6. A device for controlling the leading end portion of a web as it is being severed to form a sheet and for advancing the so severed sheet from a severing means, which comprises a plurality of parallel continuously moving belts spaced laterally apart and located at one side 50 of the path of travel of the leading end of the web, means for driving said belts at a linear speed faster than the speed at which the web is traveling, a plurality of freely rotatable rolls spaced 55 apart longitudinally along each belt and located at the other side of the path of travel of the web, and means for moving at least some of the rolls away from the belt to terminate the

driving friction of the belt on the severed sheet.

7. A device for controlling the leading end portion of a web as it is being severed to form a sheet and for advancing the so severed sheet from a severing means, which comprises a plurality of parallel continuously moving belts spaced laterally apart and located at one side 5 of the path of travel of the leading end of the web, means for driving said belts at a linear speed faster than the speed at which the web 10 is traveling, a set of freely rotatable rolls spaced apart longitudinally along each belt and located at the other side of the path of travel of the web adjacent the point of severance of the web so that the leading end of the web is under the 15 control of said belt and said rolls and is drawn out taut by the belts slipping over it, a second set of rolls located on the same side of the path of travel of the web as the first set but spaced along the belt beyond the second set, and means 20 for moving the second set of rolls away from the belts to terminate the driving friction of the belts on the sheet severed from the leading end of the web.

8. A device for controlling the leading end 25 portion of a web as it is being severed to form a sheet and for advancing the so severed sheet from a severing means, which comprises a plurality of parallel continuously moving belts spaced laterally apart and located at one side 30 of the path of travel of the leading end of the web, means for driving said belts at a linear speed faster than the speed at which the web is traveling, a set of freely rotatable rolls spaced apart longitudinally along each belt and located 35 at the other side of the path of travel of the web adjacent the point of severance of the web so that the leading end of the web is under the control of said belt and said rolls and is drawn out taut by the belts slipping over it until the so- 40 controlled leading portion has been severed to form a sheet, and thereafter the severed sheet will be carried along by frictional engagement with the belt at a higher linear speed than that at which the web is moving so that it is pro- 45 gressively separated from the body of the web, a second set of rolls located on the same side of the path of travel of the web as the first set but spaced along the belt beyond the first set, means for moving the second set of rolls away from the 50 belts to terminate the driving friction of the belts on the severed sheet, and sheet supporting means positioned to receive and support in a predetermined position the sheet so released from driving engagement with the belts. 55
